UNITED STATES PATENT OFFICE.

ALBERT MELZER, OF OSTHOFEN, GERMANY.

DEVICE FOR THE ERECTION OF BOARDINGS FOR THE PRODUCTION OF COFFERWORK
WITHOUT THE USE OF SCAFFOLDING.

Application filed September 17, 1921. Serial No. 501,480.

To all whom it may concern:

Be it known that I, ALBERT MELZER, a citizen of the German Republic, residing at Osthofen, Germany, have invented certain new and useful Improvements in Devices for the Erection of Boardings for the Production of Coffeework without the Use of Scaffolding, of which the following is a specification.

10 This invention relates to a method and a device for the erection without scaffolding, of boardings for the production of coffee work with the use of one or several pairs of planks maintained in the working position by means of tie bows.

15 According to known working methods the planks connected by holding bows or other parts of the boarding are filled up to the upper edge with filling material whereupon 20 the material is left to harden, before all the holding bows have been removed, a new boarding is put up by means of the previously used parts of the boarding and of the holding bows. The loss of time and of labour connected with this known method is avoided by a continuous working method which has been proposed and according to 25 which without regard to the hardening of the rammed in filling material—when two 30 or more pairs of planks are used—another pair of planks is placed upon the upper planks of the boarding, this new pair of planks being placed above the holding bows extending through the section of the wall to 35 be connected provisionally with the preceding pair of planks by means of holding bows, whereupon, after the holding bows of the pair of planks below the middle boarding have been depressed by means of the new 40 holding bows, the upper boarding is lowered upon the middle boarding to get ready for work.

Although this latter method forms progress over the old method the pressing down 45 of the upper boarding is difficult and requires time as the boarding has always to be correctly adjusted.

This invention shows how this inconvenience can be avoided in conserving the 50 continuous erection of the wall.

According to this improved method holding bows are fixed upon the upper pair of planks which enclose the material rammed in whereupon the lower holding bows are 55 removed and the new planks placed directly

upon the upper planks, these new planks being held by adjustable holding and straightening bows.

In order that the invention may be clearly understood, I shall proceed to describe the 60 same with reference to the accompanying drawing, wherein:—

Fig. 1 shows in side elevation the boarding and the holding bows.

Fig. 2 is a front elevation view of Fig. 1. 65

Figs. 3 and 4 illustrate, on smaller scale, the erection of the boarding and the manner in which the holding bows are used.

For continuously erecting the coffee work, holding bows B are placed upon the boarding a which is already filled with rammed in material, whereupon the holding bows B, which have hitherto held the boarding are loosened and removed together with the pair of planks which has been free. The removed planks are used for making the new boarding. The planks a which remain in place are held in the meantime merely by jaws c. These jaws c are preferably made from solid wood; they have projections at 70 the lower part which are in contact with the planks a and their upper surfaces are inwardly inclined. The jaws c are guided upon profiled irons, for instance T irons d, by means of grooves provided in their upper edge. The guiding is effected with the aid of U-shaped iron bows e which are fixed to the jaws c and grip over the guide rails d. These bows e have pressure screws f in 75 their web. 80

When the new boarding is to be put in place, the jaws c which are loosely guided upon the rails d (Fig. 4) are pressed against the planks a in position and secured in position by the tightening of the screws f. 90 95 Owing to the tightening of the screws the bows e are displaced in the direction of the arrows 1. The jaws c pivoting around the point 2 are moved with their lower ends in the direction of the arrows 3 towards the planks a so that they are pressed strongly against the same. The planks a of the old boarding can now be placed upon the planks a'. As the planks a' are held only at the ends, the planks a can be easily inserted 100 105 obliquely from above. After the insertion of the planks a and after adjusting the distance of said planks according to the thickness of the wall to be erected by means of spacing blocks g, the distance and straight- 110

ening bars *h* are placed against the planks *a*. These bars *h* are hingedly connected with the jaws *c* by means of hinges *i* and located in the space left free between the upper part 5 of the jaws and the planks.

A toggle joint *k*, adapted to be operated by a lever *l* is inserted at the upper part 10 of the jaw *c* between said jaw or the bow *e* and the straightening bar *h*. When the lever *l* is depressed in the direction of arrow 4 the toggle joint *k* is straightened in the direction of arrow 5 whereby the straightening bar *h*, pivoting around the hinge *i*, is 15 pressed against the plank *a* in the direction of the arrow 6. The levers *l* can be secured in their position in the well known manner by means of stop pins or the like. The new boarding can now be vertically adjusted by loosening or tightening the screws *f*. 20 The continuous erection of boardings for coffer work can be thus effected with only two or more pairs of planks without the necessity of mounting the planks for the fresh boarding upon the holding bows.

25 I claim:—

1. An improved holding clamp for the erection of boarding for coffer work without the use of scaffolding, comprising in 30 combination with an upper profiled guide rail, two clamping jaws adjustably guided on the lower surface of said rails, an inwardly directed projection at the lower end of each of said jaws, one U-shaped bow for each jaw fixed at the upper end of said jaw, 35 and gripping over said guide rail, a set screw in the web of each U-shaped bow, one

holding- and straightening bar for each jaw hingedly connected at its lower end with the upper surface of the inwardly directed projection of said jaw and designed to bear 40 against several boarding planks, a toggle joint between each jaw and the upper part of its straightening bar and a hand lever for each toggle joint.

2. An improved holding clamp for the 45 erection of boarding for coffer work without the use of scaffolding, comprising in combination with an upper profiled guide rail, two 50 clamping jaws adjustably guided on the lower surface of said rails having an inwardly inclined upper surface which is in contact with said guide rail at one point only, an inwardly directed projection at the lower end of each of said jaws, one U-shaped box for each jaw fixed at the inner part of 55 the upper end of said jaw, and gripping over said guide rail, a set screw in the web of each U-shaped bow, one holding- and straightening bar for each jaw hingedly connected at its lower end with the upper 60 surface of the inwardly directed projection of said jaw and designed to bear against several boarding planks, a toggle joint between each jaw and the upper part of its straightening bar and a hand lever for each 65 toggle joint.

In testimony whereof I affix my signature in presence of two witnesses.

ALBERT MELZER.
